UNITED STATES PATENT OFFICE.

GEORGE P. FENNER, DECEASED, LATE OF NEW LONDON, CONNECTICUT, BY ANNIE C. S. FENNER, EXECUTRIX, OF NEW LONDON, CONNECTICUT, ASSIGNOR TO THE BABCOCK PRINTING PRESS MANUFACTURING COMPANY, A CORPORATION OF CONNECTICUT.

CYLINDER-OPERATING DEVICE FOR PRINTING-PRESSES.

1,289,717.

Specification of Letters Patent. Patented Dec. 31, 1918.

Application filed May 9, 1918. Serial No. 233,573.

To all whom it may concern:

Be it known that GEORGE P. FENNER, deceased, late a citizen of the United States, and a resident of New London, in the county 5 of New London and State of Connecticut, invented certain new and useful Improvements in Cylinder-Operating Devices for Printing-Presses, of which the following is a specification.

- 10 The present invention consists of a cylinder tripping device for printing presses. It relates to the class of cylinder tripping devices used for two revolution presses or presses of the type wherein the cylinder 15 makes two revolutions for each printing operation or for each sheet fed. In such presses it is necessary to elevate the impression cylinder at each alternate revolution in order to separate the cylinder from the form 20 while the bed is making the return stroke. This is the periodical or automatic operation which takes place while the press is running and so long as the sheets are properly fed. It is necessary, also, to provide manually 25 controlled means for tripping the cylinder when a sheet fails to feed properly or for any other reason, so that the cylinder will remain raised during the forward stroke of the bed. There are many devices for thus 30 elevating the cylinder in some of which, only the cylinder is moved upwardly and not the intermediate gear through which the cylinder is operated. In such presses there is more or less looseness between the cylinder 35 gear and the intermediate gear while the cylinder is raised, which causes noise and vibration. In other cases, the intermediate gear is raised with the cylinder so that the former is always in full mesh with the cylinder 40 gear, even while the cylinder is raised. The present invention relates to devices of this latter class.
- The object herein is to raise the cylinder and the intermediate gear automatically or 45 periodically at each alternate revolution of the press and to provide manually controlled means for tripping the press so that the cylinder may be held up in the event that the feeder fails to feed a sheet, or for any other 50 reason. Where the intermediate gear is raised with the cylinder it has a certain limited planetary movement around the driving pinion on the main shaft, and by which pinion the intermediate and cylinder are driven,

and this planetary movement causes the cylinder to be retarded or advanced, slightly, in its rotation according to whether the intermediate gear is moving up or down. There is no acceleration or retardation of the reciprocating bed corresponding with the acceleration or retardation of the cylinder above referred to, so that the cylinder and bed are not always moving exactly the same; that is, their surface speeds are not exactly alike at all times. This fact is unimportant 55 so long as both the cylinder and intermediate rise and fall together at each alternate revolution of the press because the cylinder is free of the bed while the acceleration or retardation referred to is taking place. But 60 if the cylinder is tripped so that it is held up while the bed is making its forward stroke and if the intermediate gear is also tripped, then the relation of the cylinder to the bed is altered and the cylinder, when it 65 is tripped will not register with the bed the same as when untripped. Where a register rack is provided on the bed, for coöoperating with a gear segment on the cylinder there 70 may be injury to the register rack or segment, or both. The present invention is intended to prevent this. During the return of the cylinder in the untripping operation it bears the same relation to the bed that it 75 did before it was tripped. The planetary motion of the intermediate gear and its effect on the cylinder are the same at all times. Other advantages will be pointed 80 out in the detailed description hereinafter.

Figure 1 is a side elevation of a flat bed, 90 two revolution press, showing only such parts as are necessary to an understanding of the present invention.

Fig. 2 is an end elevation thereof.

Fig. 3 is an elevation of parts of the present mechanism, showing the cylinder at the completion of the printing stroke and showing the bed in its forward position.

Fig. 4 is a similar view but with the cylinder tripped at the moment the printing 100 operation would commence if the cylinder were not tripped, and

Fig. 5 is an enlarged elevation of the mechanism for lifting the intermediate gear.

In Fig. 1 the parts are shown just as the bed is about to go forward in the printing stroke, the manually controlled tripping device being out of operation. The side frames

of the press are partly shown at 1 and the particular form of these frames has no particular bearing on the present mechanism. The impression cylinder 3 is adapted to take the sheets from the feed board 4 by means of any known devices adapted for the purpose and this cylinder carries a sheet around with it so that the sheet receives the impression from a form carried upon the reciprocating bed 5. The bed reciprocates back and forth in a horizontal line, the mechanism for reciprocating the bed not being shown herein because the present invention requires no modification of the bed driving mechanism. At 6 is shown a shaft which carries the drive pinion 7 from which the power for revolving the impression cylinder is taken. The pinion 7 meshes with and turns the intermediate gear 8 mounted on the shaft 9 and the intermediate gear in turn meshes with the gear 10 on the cylinder shaft 11. Thus, the operating power for revolving the cylinder is transmitted from the shaft 6 through the pinion 7, the intermediate 8 and the cylinder gear 10. As is well understood in the art, in two revolution presses the cylinder makes a complete revolution while the bed 5 is going forward on the printing stroke and another revolution while the bed 30 is going backward on the return stroke. When the bed is going forward (except when the manual trip is operated) the cylinder is down but while the bed is making its return stroke the cylinder is raised so that the sheet or cylinder will be out of contact with the form on the bed.

In the form of the invention illustrated herein, many of the parts of the automatic raising and lowering device are utilized as part of the manually controlled tripping device. It will be convenient to first consider the mechanism as performing the usual or automatic raising and lowering operations. There is a shaft 12 which is driven from the shaft 6 by means of a small gear 13 on the latter and a larger gear 14 on the shaft 12. The shaft 12 has fixed thereto a cam 15 which operates on the rollers 16 disposed at opposite sides of the cam, to reciprocate a hook bar 17 which carries these two rollers 16. This is one known method of operating a hook bar and it is understood in the art. The hook bar 17 toward its forward end has a hook 18 in front of which there is a recess 19 to receive the member 20. The member 20 is carried upon a rocker 21 which is journaled in the side frames 1 and extends across the press and serves in the nature of a shaft. On the side of the press the rocker 21 has fixed to it an arm 22 to which there is fulcrumed one end of a link or pitman 23. The other end of the pitman 23 is fulcrumed to an arm 24 which is part of a well known eccentric device 25. The purpose of the eccentric device is to operate on the cylinder

shaft 11 to raise and lower the cylinder and as eccentric devices for this purpose are well known in the art a detailed description thereof is unnecessary in the present case. It is to be understood that the present case is not necessarily limited to an eccentric device for raising and lowering either the cylinder or the intermediate gear.

It will be apparent from the above that so long as the hook bar 17 is hooked to the member 20 the rocker 21 will be caused to oscillate as the hook bar reciprocates under the action of the cam 15; and the oscillations of the rocker cause the cylinder to rise and fall periodically and in time with the reciprocations of the bed 5.

There is a link 26 fulcrumed at 27 to the hook bar and at its other end, it is fulcrumed at 28 to an arm 29 on a shaft 30 which extends across the press and which is shown extending through sockets in the rocker 21. Through the link 26 and arm 29 the hook bar oscillates the shaft 30. At the side of the press there is an arm 31 fixed to the shaft 30 and to this arm there is fulcrumed at 32 a coupling 33. The pitman 34 has one end passed through a bearing 35 in the coupling 33 and upper and lower nuts 36, 37 threaded on the pitman 34 engage the bearing 35 between them and thus secure the lower end of the pitman to the coupling so that when the arm 31 oscillates with the shaft 30 the pitman will rise and fall. The upper end of the pitman is fulcrumed to an arm 38 which operates an eccentric device 39. The eccentric device 39 operates on the shaft 9 to raise and lower the intermediate gear. The eccentric device 39 performs the same function as to the intermediate gear that the eccentric 25 does to the cylinder.

The present invention is adapted to be used regardless of whether or not a register rack is employed on the bed, but a register rack is shown herein.

The rack 40 is attached to the forward end of the bed 5 and it is adapted to register with the toothed segment 41 on the cylinder at the commencement only of the forward printing stroke of the bed. The purpose of the register rack is well known so that further description is unnecessary here.

The operation of the above parts may be considered at this point. Assuming the press to be running with the tripping device out of operation, the bed 5 and the cylinder 3 will be about in the position shown in Fig. 1 at the commencement of the forward or printing stroke. The member 20 will be engaged in the recess 19 of the hook bar 17. The register rack 40 will be in mesh with the gear segment 41 of the cylinder. Both the cylinder and intermediate gear are in their lower position, so that the intermediate gear is in full mesh with the driving pinion 7 and with the cylinder gear 10. Obviously

the pitman 23 and pitman 34 will be in their lower positions. As the parts proceed from this condition the bed will go forward or to the left in Fig. 1, the cylinder 3 revolving accordingly, and the gear segment 41 and the register rack 40 will disengage soon after the forward stroke commences. The bed 5 will go forward to its extreme position, the sheet being printed during the forward motion of the bed, and the bed will then reverse and move back to its extreme rearward position. When the bed reverses and begins its rearward motion the hook bar 17 also reverses and it moves forwardly. This action of the hook bar oscillates the rocker 21 and the shaft 30 and both pitmen are moved upwardly and they cause the intermediate gear and the cylinder to rise until the cylinder is free of the bed, so that the latter may make its return stroke. The gear segment 41 on the cylinder will not mesh with the register rack 40 during this return motion of the bed as they move slightly in advance of each other.

When the intermediate gear is lifted in the manner described it partakes of a slight planetary motion in relation to the driving pinion 7 and this slightly alters the relation of the cylinder and bed, but this is immaterial because the bed is on its return stroke.

The purpose of raising the intermediate gear with the cylinder is, as previously pointed out, to keep the intermediate gear in full mesh with the cylinder gear when the cylinder is raised to prevent the noise and vibration which would result if these gears were not maintained in full mesh.

By the time the bed reverses and commences its second forward motion the hook bar 17 will have been moved backward again and the cylinder and the intermediate gear will have been lowered again to the position shown in Fig. 1. When these are lowered the intermediate gear partakes of a slight planetary motion about the driving pinion 7 but this time the planetary motion is a reversal of its planetary motion when the intermediate gear was raised. This second or return planetary motion brings the cylinder to register with the bed so that the register rack 40 will properly mesh with the gear segment 41 for the second forward or printing stroke.

There is shown a treadle 42 for manually controlling the tripping of the cylinder in order that the latter may be held up while the bed is moving forward. This treadle is fulcrumed to a lever 43 which is pivoted to a bracket at 44. The other end of this lever has a roller 45 engaging the inclined surface 46 of the hook bar 17. The treadle is held up by a spring 47 fastened at one end to the lever 43 and having its other end fixed and when the treadle is up the hook bar remains

down so that the member 20 is engaged in the recess 19 of the hook bar. That is to say, so long as the treadle remains up the parts operate as above described. When the press feeder desires to trip the cylinder he 70 presses down on the treadle, holding it down as long as he desires the cylinder to be tripped or he may swing the treadle and lock the pin 48 under the stop 49 and the treadle will then remain down until released. 75

When the treadle is pressed down, the lever 43 is rocked in opposition to the spring 47. The arm of the lever 43 which carries the roller 45 will lift the forward end of the hook bar 17 and disengage this bar from the member 20. If the treadle is depressed while the hook bar is in its rearmost position the member 20 will be disengaged from the recess 19 but the projection 18 will carry the member 20 forward again and leave it in this position, with the cylinder raised, until the latter is untripped. While the hook bar 17 is disengaged from the member 20 the former continues to move back and forth but 90 since it no longer engages the member 20 the cylinder ceases to rise and fall, remaining in its raised position. The cylinder, however, continues to revolve. While the treadle is depressed there is no change in the operation 95 of the intermediate gear. That is to say, the connection between the hook bar 17 and the shaft 30 remains unchanged, so that as the hook bar reciprocates, the link 26 transmits motion to the arm 29 and the shaft 30 and 100 the intermediate gear is raised and lowered at each alternate revolution of the press the same as if the cylinder were not tripped. It will be understood that the rise and fall of the intermediate gear is not sufficient to disengage the intermediate gear from the cylinder gear but these will naturally not be in full mesh while the intermediate gear is down, and the cylinder is up but in the present case this only happens when the press is 110 tripped. So long as the treadle remains down the parts will continue to operate as just described.

When the treadle is released the lever 43 will be rocked back by the spring 47 and this will allow the forward end of the hook bar to descend until the member 20 reengages in the recess 19. Upon this reengagement the device which raises and lowers the cylinder will again be set into operation the same as 115 before the cylinder was tripped.

It will be obvious that while the cylinder remains tripped the intermediate rises and falls as before and it has the slight planetary movement about the driving pinion 7 125 previously referred to.

The planetary motion will momentarily retard and advance the cylinder slightly the same as before the cylinder was tripped and it follows that if the segment 41 and register 130

rack 40 properly meshed at the commencement of the printing stroke when the cylinder was untripped they will likewise mesh when the cylinder is tripped. The object of 5 the present invention is to preserve the proper register as between the cylinder and bed in a structure wherein the intermediate gear is periodically lifted with the cylinder.

Having described the invention, what is 10 claimed is:

1. A printing press having a bed, an impression cylinder coöperating therewith, a cylinder gear, and means for operating the cylinder gear, comprising a driving gear or pinion and an intermediate gear interposed between said pinion and said cylinder gear, means for raising and lowering said impression cylinder in relation to the bed, means for raising and lowering the intermediate gear, and means for tripping said cylinder independently of the intermediate gear whereby the intermediate gear will rise and fall while the cylinder is tripped.

2. A printing press having a bed, an impression cylinder coöperating therewith, a cylinder gear, and means for operating the cylinder gear, comprising a driving gear or pinion and an intermediate gear interposed between the pinion and said cylinder gear, 30 means for automatically raising and lowering the impression cylinder in relation to the bed, means for automatically raising and lowering the intermediate gear, and means for tripping said cylinder independently of the intermediate gear whereby the intermediate gear will rise and fall while the cylinder is tripped.

3. A printing press having a bed, an impression cylinder coöperating therewith, a cylinder gear, and means for operating the cylinder gear, comprising a driving gear or pinion and an intermediate gear interposed between the pinion and said cylinder gear, means for automatically raising and lowering the impression cylinder in relation to the bed, means for automatically and periodically raising and lowering the intermediate gear simultaneously with the raising and lowering of said cylinder and means for 50 tripping said cylinder independently of the intermediate gear whereby the latter will rise and fall while the cylinder is tripped.

4. A printing press having a bed, an impression cylinder coöperating therewith, a cylinder gear and means for operating the cylinder gear comprising a driving gear or pinion and an intermediate gear interposed between the pinion and said cylinder gear, means for automatically raising and lowering the impression cylinder in relation to the bed, means for automatically raising and lowering the intermediate gear simultaneously with the raising and lowering of said cylinder, common power means for operating 60 both of said raising and lowering means,

and means for tripping said cylinder independently of the intermediate gear whereby the latter will rise and fall while the cylinder is tripped.

5. A printing press having a bed, an impression cylinder coöperating therewith, a cylinder gear and means for operating the cylinder gear, comprising a driving gear or pinion and an intermediate gear interposed between said pinion and said cylinder gear, 70 means for raising and lowering said impression cylinder in relation to the bed, means for raising and lowering the intermediate gear, power means for operating said raising and lowering means and a treadle adapted to trip the cylinder independently of the intermediate gear whereby the latter will rise and fall while the cylinder is tripped.

6. A printing press having a bed provided with a register rack, an impression cylinder coöperating with the bed and having a gear segment coöperating with said register rack, a cylinder gear and means for operating it comprising a driving gear or pinion and an intermediate gear interposed between said pinion and cylinder gear, means for raising and lowering said impression cylinder in relation to the bed, means for raising and lowering the intermediate gear and means for tripping said cylinder independently of the intermediate gear whereby the latter will rise and fall while the cylinder is tripped.

7. A printing press having a bed, an impression cylinder coöperating therewith, a cylinder gear and means for operating it comprising a driving gear or pinion and an intermediate gear interposed between said pinion and cylinder gear, means for raising and lowering the impression cylinder, means for raising and lowering said intermediate gear, 105 gear, a reciprocating hook bar adapted to operate both said raising and lowering means and means for uncoupling said hook bar from said cylinder raising means independently of said intermediate gear raising means for the purpose set forth.

8. A printing press having a bed, an impression cylinder coöperating therewith, a cylinder gear and means for operating it comprising a driving gear or pinion and an intermediate gear interposed between said pinion and said cylinder gear, oscillating means for raising and lowering the cylinder, oscillating means for raising and lowering said intermediate gear, a reciprocating hook 115 bar for operating both said oscillating means and means for disengaging said hook bar from said first oscillating means, said hook bar being adapted to operate said second oscillating means when disengaged from 120 said first oscillating means.

9. A printing press having a bed, an impression cylinder coöperating therewith a cylinder gear and means for operating it comprising a driving gear or pinion and an 130

intermediate gear interposed between said pinion and cylinder gear, oscillating means for raising and lowering the cylinder, oscillating means for raising and lowering said 5 intermediate gear, a reciprocating hook bar adapted to engage and disengage said first oscillating means, a pivoted connection between said hook bar and said second oscillat-

ing means, and means for disengaging said hook bar from said first oscillating means. 10

Signed at New London, in the county of New London and State of Connecticut, this 6th day of May 1918.
